UNITED STATES PATENT OFFICE.

WILLIAM C. RASTETTER, OF FORT WAYNE, INDIANA.

STEERING-WHEEL.

1,331,210.

Specification of Letters Patent. Patented Feb. 17, 1920.

Application filed February 14, 1919. Serial No. 276,949.

To all whom it may concern:

Be it known that I, WILLIAM C. RASTETTER, a citizen of the United States of America, and resident of Fort Wayne, in the 5 county of Allen and State of Indiana, have invented certain new and useful Improvements in Steering-Wheels, of which the following is a specification.

This invention relates to improvements in 10 steering wheels for automobiles consisting of a circular wooden rim mounted upon a metallic spider, and the object thereof is to so form the rim and spider as to effect rigid connections between the ends of the arms 15 of the spider and the rim without external obstructions or blemishes occasioned by the usual fastening means; and another object is to so form and apply the ends of the spider-arms to the rim as to avoid loosening 20 of their connections therewith.

The objects of the invention are accomplished by the construction illustrated in the accompanying drawings, in which:—

Figure 1 is a plan view of the steering- 25 wheel with parts thereof shown broken away and in section;

Fig. 2 is a transverse section of Fig. 1 approximately on the line $x-x$ thereof; and

Fig. 3 is a detailed view showing a plan 30 of the end of one of the spider-arms upon a larger scale.

Similar characters of reference indicate corresponding parts throughout the several views and referring now to the same:

35 1 is a wooden rim constructed with a series of gains 2 made in its inner side from each of which extend a pair of divergent holes 3. 4 is a metallic spider having a series of outwardly and upwardly diverging arms 5, 40 each of which has at its outer end a head 6 from which extends outwardly a pair of prongs 7 projecting in parallel relation with each other and adapted to enter the corresponding holes 3 and to be spread apart 45 therein as the spider is forced into position in connection with the rim.

In making the steering wheel the spider is formed of pliable metal that will admit of

the arms being bent sufficiently upward as to admit of the rim to completely encompass 50 the spider, and the spider is then positioned for the introduction of the prongs into the holes. The spider-arms are bent outwardly so that the prongs are forced into the holes and spread to conform therewith by pressure exerted against the spider. In performing this operation the wooden rim is held tightly in a clamp (not shown) to prevent splitting or otherwise becoming injured by the forcible insertion of the spider. 60

By means of this construction the heads 6 project into the corresponding gains 2 and the prongs are concealed within the body of the rim, and the usual attaching projections and securing screws that ordinarily are employed and obstruct the exterior of the rim are eliminated leaving the rim entirely free 65 of their objectionable presence.

What I claim is:—

1. In a steering-wheel, a rim having a 70 series of gains made in its inner side and a pair of divergent holes extending from the bottom of each gain into the body of the rim; and a spider having outwardly and upwardly extending arms, the outer ends of 75 which have heads respectively adapted to fit in the corresponding gains in the rim and two prongs forcibly spread into the pair of holes leading therefrom.

2. In a steering-wheel a rim having a 80 series of holes in its inner side arranged in divergent pairs, and a spider having arms from the outer ends of which extend parallel prongs adapted to be spread as they are forcibly projected into the corresponding 85 pair of divergent holes so as to conform therewith, said spider being so constructed as to admit of the introduction and lodgment of the prongs into the rim by bending its arms outwardly. 90

In testimony whereof I affix my signature in presence of two witnesses.

WILLIAM C. RASTETTER.

Witnesses:

MATILDA METTLER,
WALTER G. BURNS.
